FRINGE

Juan J. R. Vinegla, Mula, Spain, assignor to Casa Vinegla,
S.L. (Murcia), Spain, a Spanish corporation

Filed Nov. 22, 1965, Ser. No. 88,195

Claims priority, application Spain May 20, 1964

Term of patent 14 years

(Cl. D3—32)

The single figure is an elevational view of a fringe showing my new design, the fringe being continuous on either side as indicated.

This application is a continuation-in-part application of my copending applications, Serials Nos. D.82,664 and D.82,665, filed November 18, 1964 and now abandoned.

I claim:

The ornamental design for a fringe, substantially as shown and described:
